COUNTING MACHINE

George Cobden, Chicago, Ill.

Application April 1, 1939, Serial No. 265,409

1 Claim. (Cl. 235—98)

This invention relates to a counting machine and is particularly designed to be used for counting goods delivered to a laundry for the purpose of being washed or cleaned such as towels, sheets, pillow cases, etc. The number of pieces are counted when first brought to the laundry so that a correct delivery can be made and a proper charge can be made for the work done when the goods are returned to the owner. Heretofore such goods were counted by an individual picking up each piece and dropping it into another container provided for the purpose, but such counting was monotonous and tiresome besides the count thus made may often be incorrect. Another manner of counting often resorted to was to have the individual who was picking up each piece of goods operate a lever each time to register the count on a standard counting machine.

By the use of this counting machine the individuals assigned to do the counting of the goods need not have their mind on the number of goods counted nor do they have to operate any pull cord or lever. Thus their mind is free to dwell on other subjects and the work is not monotonous or tiresome. The number of pieces of goods is properly and correctly counted. The counter may not be close to the person handling the goods but may be located in another room and not in view of the operator.

This counting machine consists of a portable frame which is easily placed on a box or container ordinarily used in laundries and has a rectangular frame the center of which contains a curtain made of thin flexible material. This curtain hangs on an upper rod which is adjustably secured to the upper rail of the frame and has another rod secured to its lower edge. The ends of the lower rod are guided in suitable vertical slots in the upright rails of the frame so that when an object is thrown against the curtain the lower rod will be lifted. When the lower rod is thus lifted it will make electrical contact between two points arranged for the purpose.

These two electrical contacts are arranged in a circuit including a source of electric energy and a solenoid which operates a standard counter. A further object of this invention is to so arrange a plurality of electric sockets in and about a laundry so that the electric plug on the frame above described can be plugged into any one of the numerous sockets and the one counter, which may be in the laundry office, will always be operated when a piece of material is thrown against the curtain above described.

To describe this invention so that others versed in the art to which it belongs can make and use the same it is illustrated on the accompanying sheet of drawings forming a part of this specification and in which:

Figure 1 is a front elevation of a counting machine made in accordance with this invention; Fig. 2 is a side elevation of the same and Fig. 3 is a diagrammatical view showing how the laundry counter can be used in a modified form.

Similar reference numerals refer to similar parts throughout the several views.

The device shown in Figs. 1 and 2 is designed to be complete in itself, that is, the counter 4, the solenoid 5, and the battery 6 are all mounted on the frame comprising the base 7, side uprights 8, braces 9 and the top bar 10. The base 7 has depending lugs 11 at each end to prevent it from moving off a box or similar receptacle.

Fig. 3 shows a modification in which the electrical connections are arranged in such manner that the frame base 7 may be placed on any one of a plurality of receptacles in different locations of the laundry room and the necessary electrical connection made by plugging into any one of the numerous sockets provided for the purpose and the one counter 4 may be located in the office department or at any distance from the frame base 7.

The detail construction of the parts may be changed without in the least departing from the spirit of the invention as described. The top bar 10 of the frame is provided with two vertically extending holes through which loosely extend the rods 12 having their upper protruding ends threaded to receive the thumb nuts 13, and the lower ends of said rods 12 are attached to the horizontally extending bar 14 which supports the upper edge of the flexible curtain or sheet 15, and the lower edge of the curtain 15 has a horizontally extending rod 16 attached to it whose ends are free to slide vertically in grooves 17 provided in the uprights 8 of the frame. The lower rod 16 may be made sufficiently heavy to at all times hold the curtain 15 taut but in the drawing two light springs 18 are connected between the rod 16 and the base 7 for such purpose. The central portion of the rod 16 which is made of electrical conducting material is located a short distance below the electrical conductor 19 so that when the rod 16 is lifted slightly it will make electrical contact with the conductor 19, which preferably is made to be a wiping contact.

The space between the rod 16 and the conductor 19 may be varied as desired by turning

the thumb nuts 13 on rods 12 secured to the upper rod 14. An electrical conductor 20 extends from the middle portion of rod 16 to one pole of the battery 6 and another electrical conductor 21 extends from the contact 19 to one pole of the coil of solenoid 5 and another electrical conductor 22 extends from the other pole of the coil of solenoid 5 to the other pole of the battery 6. The core 23 of solenoid 5 is free to slide vertically and is connected by rod 24 to the free end of the operating lever 25 of the counter 4. Thus every time an electrical contact is made between rod 16 and electrical conductor 19 the operating lever 25 of the counter 4 will be lifted.

In operation the laundry counter is positioned above a receptacle by placing the base 7 on same spanning the open top of the receptacle and the depending lugs 11 will retain the base in proper position. The operator picks up the pieces of laundry or goods to be counted one by one and throws each piece against the curtain 15 from whence each piece will drop by force of gravity into the receptacle. As each piece hits or strikes against the curtain 15 it will be moved sufficiently out of its vertical position to lift the rod 16 into contact with the conductor 19 and this will cause the electrical current to energize the solenoid 5 and tally one on the counter 4 as above described. Thus each piece of goods will be registered on the counter 4 without in any way requiring the operator to give any attention to same, and no confusion can occur in the count although the operator may leave her position for a time, and no pencil or paper is required.

In the modification shown in Fig. 3, the two wires of a light circuit are shown at 26 and 27, these are connected by wires 28 and 29 to binding posts of a transformer 30, and other two wires 31 and 32 are connected to other binding posts of said transformer 30 to secure the proper low voltage in wires 31 and 32 to operate the solenoid 5. The wire 31 forms electrical connection between the transformer 30 and the coil of solenoid 5 and another wire 33 is connected to the other end of the coil of solenoid 5 so that it is only necessary to make electrical connection be-

tween wires 32 and 33 to energize the coil of solenoid 5. The wires 32 and 33, preferably in a single cable, are strung about the laundry wherever any goods may be desired to be counted. At the desired locations about the laundry wall plugs 34 are secured and each wall plug is connected by wires 35 and 36 to the wires 32 and 33; thus the electrically wired plug 37 which is connected to the wires 20 and 21, above described, can be plugged into any one of the wall plugs 34 as desired. Any contact made between rod 16 and contact 19 will energize the coil of solenoid 5 no matter to which of the numerous wall plugs 34 the wire plug 37 is connected; the electric circuit passing from one binding post of the transformer 30, over wire 31, through the coil of solenoid 5, over wire 33, one of the wires 36, wire 20, rod 16, contact 19, wire 21, one of the wires 35, and wire 32 back to the other binding post of transformer 30. It will be understood that a battery may be substituted for the transformer 30 and the same operations as above described will take place each time the rod 16 and conductor 19 make electrical contact.

Having thus fully described the invention what is claimed and desired to be secured by Letters Patent of the United States is:

The combination in a portable counting machine of a supporting structure formed to fit on the top of a container and including a rectangular frame having a base, two side uprights having vertical slots in their opposing faces, and a top piece all four rigidly secured together, a vertically extending flexible curtain having its upper edge adjustably secured to the said top piece, means for adjusting the upper edge of the curtain vertically toward and away from said top piece, said means comprising a screw and a nut, a horizontally extending rod secured to the lower edge of said curtain having its ends slidably fitting into the vertical slots in each side upright whereby flexing of the curtain will cause the said rod to move vertically in the slots, a register and means controlled by the upward movement of said rod for actuating said register.

GEORGE COBDEN.
